CATHODE-RAY TUBES OF THE FOCUS-MASK VARIETY

Richard H. Godfrey, Landisville, Pa., assignor to Radio Corporation of America, a corporation of Delaware
Filed Jan. 27, 1958, Ser. No. 711,249
5 Claims. (Cl. 315—9)

This invention relates to improvements in color-kinescopes and other cathode-ray tubes of the kind wherein the beam-electrons are subjected to a focusing action by elemental mask-aperture lenses immediately prior to impinging upon the screen or target of the tube. Such cathode-ray tubes are herein referred to as being of the "focus-mask" variety.

If the screen and the envelope walls of a focus-mask tube are operated at the same high potential and the mask is operated at a lower potential, the field between the tube's plane-of-deflection and the mask decelerates the beam-electrons, and the field between the mask and the screen accelerates the beam-electrons. Consequently, the electrons before reaching the mask are refracted away from the tube-axis and, after passing through the mask-apertures are refracted toward the tube-axis. This refraction phenomena may be considered to be separate from the focusing effect produced by the mask-apertures acting as lenses. Refraction of the beam-electrons away from the tube-axis as they approach the mask is beneficial in that it reduces the scanning power required of the yoke. However, unless the outward refraction effect before the mask is exactly off-set by the refraction in the other direction, between the mask and screen, a phosphor dot (or line) screen prepared by optical projection in a "light-house" (as used in the manufacture of mosaic-screens for use in "shadow-mask" tubes) cannot be employed since the terminal points of the light paths and the electron paths on the phosphor-screen will not coincide. If, for example, the mask of a 90° shadow-mask tube is operated at a low potential, as required in the operation of a focus-mask tube, the optical and electron terminal points for rays passing through a given mask-aperture near the edge of the tube are out of register by about 0.200". It might at first glance appear that this amount of misregister could be corrected by doing two things: (1) Reducing the mask to light-source distance during the screen-plotting operation to correct the linear component of the misregister and (2) interposing an optical lens between the light source and mask (as taught by Epstein, Kaus and Van Ormer in U.S. Patent 2,817,276, see also co-pending application Serial No. 585,254, now U.S. Patent No. 2,885,935) to correct the non-linear component. In trying to do these two things, however, it has been found (1) that the light source-to-mask distance is too short to be practical due to severe non-uniformity of illumination caused by inverse square law fall-off, increased magnification of light source, etc. and (2) that the optical lens required would have to be exceedingly strong and consequently difficult to make and to use.

The present invention may be said to be predicated in part upon an appreciation of the fact that the solution of the problem of "misregister" in tubes of the focus-mask variety does not reside in refinements in the light-optical method employed in laying-down the mosaic of color-phosphor areas on the screen-plate of present-day color tubes. Instead, the present invention provides a cathode-ray tube of the focus-mask variety wherein a plurality of field electrodes circumscribing the space between the plane-of-deflection and the mask operate to modify or shape the decelerating electrostatic field in said space. Proper adjustment of these fields, and of the field in the mask-to-screen space, subjects the beam-electrons to refractive effects which cause said electrons to approach the

2

screen along curved paths that terminate at the screen-end of straight lines drawn from the screen through the centers of the mask apertures substantially to points whereat the axes of said electron-beams pass through said plane-of-deflection. With the principal amount of misregister thus removed, the light-optical methods of the Epstein, Kaus, and Van Ormer disclosures can easily be applied if necessary to obtain a higher degree of correction.

The invention is described in greater detail in connection with the accompanying single sheet of drawings, wherein:

FIG. 1 is a plan view, partly in section, of a 3-gun tri-color kinescope of the focus-mask dot-screen variety which is provided, in accordance with the invention, with a plurality of field electrodes circumscribing the space between the plane-of-deflection and the mask of the tube and an appropriate energizing circuit for said field electrodes; the drawing being marked with equipotential lines indicative of the decelerating electrostatic field in said space and with other lines illustrative of the path of the beam-electrons through said decelerating field and,

FIG. 2 is an enlarged fragmentary view in perspective of the screen-unit of the tube of FIG. 1.

The 3-beam, tri-color, focus-mask, dot-screen, color-kinescope 1 shown in FIG. 1 comprises an evacuated all-glass envelope having a bulbous cone portion 3 which terminates at one end in a neck 5 and, at its opposite end, in a front-end portion or "cap" 7. The cap 7 terminates in a curved face-plate 9, the concave inner surface of which comprises the mosaic screen 11 of a bi-part screen-unit 11, 13 of the focus-mask variety.

The mosaic screen 11 (see FIG. 2) comprises a multiplicity (usually 300,000 or more) of "triads" (i.e. groups-of-three) of red (R), blue (B) and green (G) color-phosphor dots. The phosphor-dots are here arranged in a hexagonal pattern; that is to say each dot is surrounded by six other dots, alternate ones of said other dots being of a second color-response characteristic and the intermediate ones of said other dots exhibiting a third color-response characteristic. An electron-transparent, light-reflecting, metallic (e.g. aluminum) film 11f (FIG. 1) covers the entire target surface of this dot-like mosaic-screen. A suitable electrical terminal, exemplified by the lead-wire 11w extends from the screen electrode 11f to the exterior of the envelope where it is shown connected to a source of voltage, V.

The other element, or "focus-mask," of the bi-part screen-unit 11, 13 preferably comprises a suitably curved thin-metal plate 13 containing a multiplicity of apertures 13a arranged in the same systematic (hexagonal) pattern as the phosphor screen-dots of a given color, there being one mask aperture for each triad (RBG) of dots. The mask has an integral rim or frame 15 and is supported about said rim on three or more pegs 15p which project radially inward from the inner surface of the cap portion 7 of the envelope. The connection between the pegs 15p and the frame 15 is such as to permit the mask to be removed from the cap during the three emulsion-coating and developing operations incident to laying down the three color-phosphors (RBG) on the glass screen-plate 9. The mask 13 is maintained at a potential considerably lower than that of the screen-electrode 11 in order to establish a beam-focusing field (not shown) about each mask-aperture in the space q between the mask and the screen. The required voltage is here shown as applied to the mask 13, from the source V, through a lead 13w connected to the mask-frame 15. Appropriate voltages are marked on the drawing.

The tubular glass neck 5 of the envelope 1 contains a battery of three electron-guns 17r, 17b, and 17g each of which is allotted to a particular screen-color. The guns are here shown arranged delta (Δ) fashion about the long

axis $x-x$ of the envelope (as in Schroeder U.S. Patent 2,595,548) so that the three beams r , b , and g converge adjacent to the surface of the mask 13 where their paths cross and proceed to the different color-phosphor dots. (In order to simplify the drawing only the path of the "red" beam r is marked within the bulbous part 3 of the envelope.) Alternatively, the guns may be arranged "in line," or a single beam may be employed, in which latter case auxiliary means may be provided as, for example, in Jenny 2,611,099, for sequentially shifting the single beam to positions corresponding to that of the several beams in a multigun tube.

As is now more or less standard practice the red, blue and green beams are subjected to dynamic convergence forces for maintaining them converged at or near the surface of the mask throughout their scanning movement. In the instant case the dynamic convergence forces are applied to the separate beams by three internal pole pieces 19 actuated by small electro-magnets 21 in the manner described in greater detail by Albert M. Morrell in U.S. Patent 2,752,520. U.S. Patent 2,751,519 to Albert M. Friend may be referred to for other electromagnetic (and electrostatic) types of dynamic beam-convergence means. In FIG. 1, as in the Schroeder patent (2,595,548) the required horizontal and vertical scanning movements are applied to all three electron-beams from the guns 17 by a common deflecting yoke 23. The "normal" plane-of-deflection is indicated in FIG. 1 by a straight line $P-P$ extending through the yoke in a direction normal to the central axis $x-x$ of the tube.

As thus far described the color-kinescope shown in the drawings is of more or less conventional construction. The indicated mask and screen voltages used to establish a focusing field about each mask aperture (13a FIG. 2) are also conventional. With the mask and the screen energized in the manner above described the beam-electrons pass through a decelerating electrostatic field in their transit from the electron-guns 17 to the mask 13 and an accelerating electrostatic (focusing) field in traversing the mask-to-screen space (q FIG. 1). If the entire electrode arrangement in this tube were in fact conventional, the second-anode (25 in the drawing) would extend (for example in the form of a conductive coating on the inner wall of the bulb) from the leading end of the gun(s) 17 to a region adjacent to the mask-frame and would ordinarily be operated at the same ulti potential as the screen. With such an arrangement the terminals of the equipotential surfaces (of which such a lens-field is comprised) would all be "funneled" into the space between the edge of the mask frame and the adjacent edge of the second-anode. The equipotential surfaces in such a conventional tube thus exhibit changes in contour which subject the beam-electrons to a high degree of outward refraction. The refraction becomes very high in the region where the beams approach the limits of their scanning movements. As previously pointed out, while it is possible to compensate for the resulting misregister by the use of a very strong optical-lens during the screen plotting operation it is not always practical to do so.

The present invention provides a series of field electrodes (later described) circumscribing the space between the plane-of-deflection and the mask. These added field-electrodes, when appropriately energized, operate to so alter the contour of the equipotential surfaces e (of which the decelerating electrostatic field in said space is comprised) that the electron beams are not subject to an excessive degree of refraction but on the contrary are refracted outwardly only a sufficient amount along curved paths (r) to compensate for the inward refraction between mask 13 and screen 11 such that a straight line $A-A$ drawn from the point of impact on the screen 11 through the center of the mask-apertures 13a projects back substantially to the appropriate color centers "R," "B," and "G" (FIG. 2) in the deflection plane $P-P$ for all screen radii.

In the instant case, one of the aforesaid series of field electrodes comprises the metal frame or rim 15 upon which the mask is supported on the other electrodes in the series comprise three electrically conductive bands 25, 26, and 27 disposed on the inner surface of the bulb in axially spaced insulating relationship with respect to the mask frame 15. The first conductive band 25 may form part of the second-anode of the tube and extends from the guns 17 (to which it is connected), through the plane-of-deflection $P-P$, into the bulb 3 a limited distance (say 3.2 inches in a 21" tube as measured from said plane $P-P$ along the central axis of the tube). This first field-electrode 25 is preferably maintained at the same (ultor) potential as the screen, as is indicated in the drawing by the position of its lead-wire 25w on the voltage source V . The second conductive band 26 is spaced, say .55 inch from the leading edge of the first band 25 and is about 1.7 inches wide as measured along the tube-axis $X-X$. The lead wire 26w for this second field electrode 26 is ordinarily connected to the same point on the voltage source V as the lead 13w for the mask 13 and its frame 15, though in some cases, e.g. where it is necessary or desirable to alter the position of the scanning yoke 23 to minimize over-scanning, the field-electrode 26 may be operated at a potential lower or higher than the mask, but nevertheless several thousand volts below the ultor potential applied to the screen. The third conductive band 27 is spaced approximately the same amount from the second band 26 as the second from the first (25) and extends up the bulb wall to a position whereat its leading edge lies approximately .200" from the plane of the mask frame 15. The lead wire 27w for this third band 27 is connected to the same ultor voltage point on the source V as the screen 11 and the first band 25.

The manner in which the "gap field former" of the present invention operates to straighten out the register curve will the more readily be understood by comparison with what takes place in the operation of tubes of the prior art employing a "solid" field former. (The term "gap field former" as applied to tubes of the present invention is suggested by the presence of a high voltage electrode or gap in what would otherwise be a continuous low voltage section from electrode 26 to the mask.) A "solid" type field former extends the low voltage on the mask toward the gun at the edge of the solid angle occupied by the scanning beam. Thus the equipotential surfaces of the field are so bent that the beam, as it is deflected by the yoke through increasing screen radii, approaches said surfaces more nearly perpendicularly and, consequently, is refracted less outwardly. Although this results in an increasing amount of compensation for the mask-to-screen field, and a resultant reduction in misregister, nevertheless a point is reached where further extension of the field former into the cone over-compensates at the screen-edge and a non-linearity of remaining misregister vs. screen radii results. The "gap" type field former improves upon this action by straightening out the register curve and makes it possible to attain substantially zero misregister. This is done by interposing a high voltage field (on electrode 27) between the low voltage extension (electrode 26) and the low voltage mask-assembly (13-15). The effect of such a field distribution is to straighten the equipotential surfaces (FIG. 1) in the area immediately preceding the mask. The action on the beam is then as follows: (1) It is still given an initial outward refraction in its transit from yoke to mask. Hence the saving in deflection power is maintained. (2) The beam path is then straightened out by the field due to the gap structure so that the refraction of the beam between the gun and mask substantially compensates for the refraction between the mask and screen.

Focus-mask tubes constructed and operated in accordance with the present invention possess many advantages, in addition to improved register, over the focus-mask

tubes of the prior art. By way of example, tubes of the present invention exhibit relatively low sensitivity to voltage fluctuations. This is so because the closer the auxiliary fields (provided by the electrodes 25, 26, 27, 15) come to compensating for the refracting effect of the field (between the mask and screen), the more independent said fields become to fluctuations in the voltages which form them. (By way of example: any fluctuation in the ulti voltage which increases the mask-to-screen field will also increase the strength of the auxiliary "compensating" field system on the gun-side of the mask.)

The color-tubes of the present invention are also relatively free from color-impurities resulting from "de-grouping" of the beams-spots with respect to the phosphor-dots. In this connection it will be recalled that in addition to so-called "dynamic degrouping" (which the small electro-magnets 21 are designed to correct) there exists (in large deflection angle tubes) a type of a de-grouping known as "static degrouping." "Static degrouping" increases with increasing deflection angle even before the dynamic component is added, is periodic with azimuthal angle, and occurs with a definite phase relationship between the three beams. It can be shown that, to the first approximation:

$$\frac{\partial d}{\partial \theta} = \frac{2q.\alpha}{\beta-1} \left[\frac{\sin \theta(\beta-2 \cos 2\theta)}{(\beta-\sin^2 \theta)^{1/2}} + \frac{\beta}{(\beta-\sin^2 \theta)^{3/2}} + 2 \sin 2\theta \right]$$

where:

d =fluorescent spot spacing from trio axis,

q =mask to screen spacing,

β =voltage ratio between screen and mask,

α =convergence angle of the beam trio,

θ =approach of trio axis to mask perpendicular.

Over the entire range of possible approach angles the slope

$$\frac{\partial d}{\partial \theta}$$

is a positive one, hence the spacing between beam center and trio center, for equal convergence angles, decreases with a decrease in the component of trio approach angle which is co-planar with the convergence angle. Since the electrostatic fields provided by the auxiliary electrodes of the present invention operate to reduce this angle, "static degrouping" is reduced.

Yet another advantage of the present invention is that it lends itself readily to the use of tube-envelopes of various shapes. Factors influencing the shape of the tube envelope are strength, stability, and appearance (such as rectangular, etc.). Optimum shape as regards these factors may be something much less than optimum as far as the beam refraction is concerned since, in the absence of any other field forming device, the bulb walls alone will shape the electrostatic field and thus determine the final net beam refraction. Inserting the field-former electrodes within the envelope permits the designer to: (1) extend the low voltage field as far down as necessary to achieve refraction compensation for small radii and (2) control the width and position of the high voltage gap to provide the proper refraction compensation for the remaining radii. These dimensions can be systematically varied by azimuthal position when refraction requirements so dictate. Greater flexibility in the design of tube shape for focus-mask tubes is therefore permitted. For example, it has proven practical to change over from a 90° metal focus-mask tube to a 90° glass focus-mask tube with resultant large changes in bulb shape. The additional design variables, which the gap field former provides, ensures better register, degrouping, etc.

In addition to the factors mentioned previously, a gap field former when connected to a voltage supply independent of the mask frame assembly can provide another degree of freedom in focus-mask operation. Altering the voltage on the field former produces a beam register

change not unlike that provided by an axial movement of the yoke; hence, the yoke may be abutting the envelope funnel at all times and small register deviations from tube to tube can be compensated for by readjustment of the field former voltage for that particular tube. Furthermore raster "pincushioning" may be altered by changing the voltage on the gap field forming ring alone.

What is claimed is:

1. In a multi-beam cathode-ray tube of the focus-mask variety having a mosaic screen the individual elements of which are disposed at the terminals of substantially straight lines drawn through the mask-apertures to respectively different points in the tube's plane-of-deflection and wherein said electron beams normally traverse doubly curved paths in their transit to respective ones of said individual screen elements by reason of (I) the refractive effect of a decelerating electrostatic field in the space between said plane-of-deflection and said mask and (II) the unequal opposite refractive effect of an accelerating electrostatic focusing field in the mask-to-screen space, the improvement which comprises: electrode means including at least three spaced apart field electrodes circumscribing said first-mentioned space, and means for applying voltages to said field electrodes to establish a potential distribution among said field electrodes such that said unequal opposite refractive effects of said accelerating and decelerating fields upon said electron-beams are rendered substantially equal, whereby the terminals of said doubly curved beam paths are caused to coincide at said screen substantially with the terminals of said straight lines.
2. The invention as set forth in claim 1 and wherein said electrode means is constituted in part by a means supporting the mask out of contact with the inner surface of said tube and, in part, by plurality of electrically conductive bands disposed adjacent to said inner surface in axially spaced relationship with respect to each other and with respect to said support means.
3. The invention as set forth in claim 1 and wherein alternate ones of said field electrodes are adapted to have a common operating potential applied thereto and intermediate ones of said electrodes are adapted to have a different common operating potential applied thereto.
4. The invention as set forth in claim 3 and wherein the screen-electrode of said tube is adapted to have an ulti potential corresponding to the first mentioned of said common operating potentials applied thereto.
5. A cathode ray tube having a plane-of-deflection comprising a screen-electrode having a mosaic target surface, an electrode mounted adjacent to said mosaic surface and containing a pattern of apertures which is systematically related to the pattern of elemental areas of which said mosaic is comprised, electron-gun means mounted adjacent to said plane-of-deflection in a position to scan said screen-electrode through the apertures in said apertured electrode, a plurality of ring-like alternate and intermediate electrodes disposed in axially spaced relationship in the space between said plane-of-deflection and said apertured electrode and through which electrons pass in their transit to said apertured electrode, means for applying a common ulti potential to said screen-electrode and to said alternate ones of said ring-like electrode, and means for applying a common lower operating potential to said apertured electrode and to the intermediate ones of said ring-like electrodes.
